CLAIM

The ornamental design for a fertilizer dispenser, as shown and described.

DESCRIPTION

FIG. 1 is a front, top and side perspective view of the fertilizer dispenser showing my new design, the water supply hose being shown broken away for the sake of convenience of illustration;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

FIG. 1

FIG. 2

FIG. 4

FIG. 3

FIG. 5

FIG. 6

FIG. 7
